UNITED STATES PATENT OFFICE.

THOMAS P. SWEENEY, OF SACRAMENTO, CALIFORNIA.

AIR-COMPRESSOR AND ATTACHMENT FOR LOCOMOTIVES.

SPECIFICATION forming part of Letters Patent No. 352,102, dated November 2, 1886.

Application filed March 23, 1886. Serial No. 196,306. (No model.)

To all whom it may concern:

Be it known that I, THOMAS P. SWEENEY, of Sacramento, Sacramento county, State of California, have invented an Improvement in 5 Air-Compressors and Attachments for Locomotives; and I hereby declare the following to be a full, clear, and exact description of the same.

My invention relates to a means for employing the ordinary steam-cylinders and valve-motion of a locomotive for the purpose of compressing air in the reservoir from which the air-brakes of a train are supplied, or for any other purpose where compressed air may 15 be used. It consists of a pipe or pipes connecting the steam chest or cylinder with the reservoir, and suitable cocks by which the communication may be made or cut off at will.

Referring to the accompanying drawings 20 for a more complete explanation of my invention, Figure 1 is a side elevation of a locomotive, showing the one cylinder and steam-chest, the air-reservoir, connecting-pipes, &c. Fig. 2 is a perspective view of the hood-operating levers and exhaust-nozzles. Fig. 3 is a transverse section of same.

A is the steam-chest, and B the cylinder of a locomotive of the ordinary construction.

C is a pipe leading backward and connecting with the air-reservoir D, a valve or cock being arranged at E to open or close communication with the steam-chest, and a check-valve at a point where the pipe opens into the air-reservoir. The valve E is operated 35 by means of a rod, F, extending backward into the cab or within reach of the engineer, so that it may be easily reached.

The operation of the apparatus will then be as follows: When it is necessary to force air 40 back to the air-brakes under the train of cars, which is coupled to the engine, the valve E is opened by the engineer by means of the rod F, and the valve-gear of the engine is reversed to a point slightly back of half-stroke; 45 then, if the engine is moving in a forward direction, the pistons of the main cylinders will act to draw air into the cylinders either through the exhaust-pipes, or, if desired, through valves or openings communicating with the 50 exterior air, and will force it through the steam-chest A, valve E, and pipe C into the air-drum D until any desired pressure has been produced, and from the air-reservoir this

air is conducted through the ordinary pipes beneath the train, so as to operate the brakes, 55 as occasion may require.

The cylinders may be temporarily connected with the open air by means of a hood or cap, G, which fits over the end of the exhaust-pipes H, its outer end communicating 60 with the open air through the front of the smoke-box, (in which the exhaust-pipes are located.) This hood or cap moves on a guide-pipe, I, so that when steam is used in the cylinders the hood can be withdrawn, so as to 55 leave a free escape for the steam through the exhaust-pipes; but when it is desired to use the cylinders for pumping-air the hood can be moved over the pipes. There will then be no danger of cinders or dirt of any kind passing 70 into the cylinders or valve-seats, so as to cut or scratch them.

The device may be used at any time when the train is under sufficient headway, and from the size of the cylinders it will pump air to a 75 high pressure in the reservoir in a very few strokes. It is especially useful and available when running down grades.

Having thus described my invention, what I claim as new, and desire to secure by Letters 80 Patent, is—

1. The combination, with the steam chest or cylinder of a locomotive-engine, of the exhaust-pipes H, a hood, G, fitted to move over said pipes, the lever engaging and moving 85 said hood, the pipe I, communicating with the exterior air and guiding the movements of the hood, and the pipe C, connecting the steam chest or cylinder with the air-reservoir, substantially as and for the purpose set forth. 9c

2. The steam-chest A, the pipe C, and the valve E, in combination with the operating-rods F, the exhaust-pipes H, the hood G, fitted on top of said pipes, and engaged and operated by suitable levers, as shown, and a pipe, 95 I, passing through the smoke-box into the exterior air and guiding the movements of the hood, all constructed and arranged to operate as herein described.

In witness whereof I have hereunto set my 100 hand.

THOMAS P. SWEENEY.
